UNITED STATES PATENT OFFICE

GUY N. HUGHES, OF ATLANTA, GEORGIA

ELECTRICAL SWITCHING DEVICE

Application filed May 18, 1928. Serial No. 278,734.

This invention appertains to improvements in electrical switching devices generally, and more particularly to a multipole block type of such devices for use in testing electrical measuring instruments, and other electrical apparatus of various classes and descriptions.

An object of the invention is to provide a switching device of the class set forth, which is of an extremely simplified but durable and 10 efficient construction and arrangement of parts, and which will be comparatively inexpensive to manufacture.

Another object of the invention is to provide an electrical test block, as hereinbefore 15 characterized, which will require only a minimum amount of space on a switch board or panel, and which will be more easily and quickly installed in position and wired in a desired circuit with less danger of open or 20 short circuit than has heretofore been the case in the installation of known types of such devices.

A further object of the invention is to provide a test switch block of the nature hereinbefore mentioned, wherein the movable 25 switch members thereof will be key operated, so that the manipulation of the same may only be accomplished by an authorized person or persons.

30 With the foregoing and other equally important objects and advantages in view, the invention resides in the certain new and useful combination, construction and arrangement of parts and circuits as will be herein- 35 after more fully described, set forth in the appended claims, and illustrated in the accompanying drawings, in which:

Figure 1 is a top plan view of a practical 40 embodiment of the invention with the cover portion thereof removed.

Figure 2 is a vertical longitudinal section taken on the line 2-2 of Figure 1.

Figure 3 is a vertical transverse section 45 taken on the line 3-3 of Figure 1.

Figure 4 is a perspective view of a form of key with which the individual switch members are to be operated.

Figure 5 is a diagrammatic view of an ar- 50 rangement of circuit connections to the im-

proved test block for testing protective relays and the like, and

Figure 6 is a view similar to that of Figure 5, but showing an arrangement of circuit connections employed for testing various electrical measuring instruments.

Referring to the drawings, wherein like characters of reference designate corresponding parts throughout the several views thereof, the embodiment of the invention, as shown therein by way of example, comprises a base block 10, which is preferably of rectangular form and made from a suitable insulating material, and is provided with posts or the like 11 rising from each of its corners to support thereon a cover 12. The cover 12, which may be of metal, or any other suitable or desired material, has side and end flanges depending from its top wall, which snugly engage about the opposite side and end edges 70 of the base 10, and its top wall formed with suitable openings to engage over the upper threaded ends of the posts 11. These threaded ends of the posts 11 are preferably of a reduced diameter to provide shoulders 75 at their lower connected ends on which the cover 12 rests when placed in position on the base 10, and nuts 13 are engaged on the threaded ends of the posts 11 to secure the cover in place. Any suitable sealing means 80 (not shown) may be employed in connection with the cover securing nuts 13 to prevent the unauthorized removal of the same when they are finally placed in position on the posts 11, as when the test block, in its entirety, has been 85 installed in its operative position.

Mounted on the upper side of the base 10, preferably in equidistantly spaced and longitudinal alignment, are a series of stationary contacts 14, 15, 16, 17 and 18 (five of such contacts being employed in the present instance), and extending in spaced parallel relation to this group or set of contacts is a second series of complementary stationary contacts 19, 20, 21, 22 and 23. Each of these several contacts aforesaid are engaged on the upper end portions of binding studs or screws 14', 15', 16', 17', 18', 19', 20', 21', 22' and 23' inclusive, respectively, and beneath the heads thereof. These studs or screws pass 100

downwardly through the base 10 to have their lower ends electrically connected to circuit leads to be hereinafter designated. The several stationary contacts of each parallel set of the same are preferably of rectangular metal block formation and arranged in transverse alinement with their opposed end edges bifurcated, as at 24. To retain the contacts of each transverse pair thereof in position with their bifurcated ends in the desired opposed relation, pins or studs 25 are engaged in the base 10, and the contacts, at one side of the respective contact studs or screws 14', 15', 16', 17', 18', 19', 20', 22' and 23' for the purpose.

Disposed on the upper side of the base 10 and midway between each pair of the complementary stationary contacts 14, 19; 15, 20; 16, 21; 17, 22; and 18, 23 are bridging contacts or switch blades 26, 27, 28, 29 and 30, respectively, which are each preferably mounted for quarter turn movements only on the upper end portions of pivot members or screws 31 beneath the heads thereof, substantially as shown, suitable supporting members or washers 32 being positioned on the bolts or screws 31 beneath the bridging contacts or switch blades 26, 27, 28, 29 and 30 to aline the same with the bifurcations in the stationary contacts with which they cooperate.

Formed in the upper face of each of the bridging contacts or switch blades 26, 27, 28, 29 and 30 are a pair of slots or recesses 33, which are preferably arranged in alinement at opposite points diametrically of the headed portions of the pivot members or screws 31 associated therewith. These slots or recesses 33 are to be engaged by the complementary projections 34 formed at the lower end of a key 35, by means of which the bridging contacts or switch blades 26, 27, 28, 29 and 30 are to be actuated to circuit closing or "on" and circuit opening or "off" positions of operation with respect to the complementary pairs of the stationary contacts aforesaid. Between the projections 34, the body of the key 35 is recessed, as at 36, to a depth sufficient to admit of the straddling of the headed portions of the pivots or screws 31 by the same, and to allow for the proper engagement of the projections 34 with the slots or recesses 33.

Also disposed on the upper side of the base 10, preferably between the stationary contacts 15 and 16, on the one hand, and the contacts 16 and 17 on the other hand, are a pair of identical bridging contacts or switch blades 37 and 38, which are mounted for limited turning movements on pivots or screws 39 and 40 respectively, and beneath the upper headed portions thereof. These bridging contacts or switch blades 37 and 38 are each also provided with slots or recesses 33' in the upper faces of the same for the en-

gagement therewith of the projections 34 of the key 35 when they are to be operated.

To allow for the proper cooperation of the bridging contacts or switch blades 37 and 38 therewith, the stationary contacts 16 and 17 are also bifurcated at their outer ends, and after the same manner as the formation of the bifurcations 24 at the inner ends of all of the several contacts 14, 15, 16, 17, 18, 19, 20, 21, 22 and 23, inclusive. As best shown in Figure 1, the opposite ends of the bridging contacts or switch blades 37 and 38 are angularly offset in opposite directions, whereby the inner ends of the same will engage the bifurcations at the inner ends of the stationary contacts 15 and 16, and the opposite or outer ends thereof with the bifurcations at the outer ends of the stationary contacts 16 and 17, the purpose of which arrangement will be hereinafter more fully explained. To allow for the desired engagement of the opposite ends of the bridging contacts or switch blades 37 and 38 in the bifurcations of the stationary contacts 15, 16 and 17 as before indicated, suitable supporting members or washers 39, similar to the supporting members or washers 32 will be engaged on the pivots or screws 39 and 40.

In Figure 5, the improved test block, as thus constructed and arranged, is shown connected in a circuit for testing protective relays or the like, the circuit connections whereof being as follows: from the three terminals of a current transformer T, coupled to the main line conductors a, b and c, tap offs 40, 41 and 42 are connected directly to the binding studs or screws 15', 16' and 17' of the stationary contacts 15, 16 and 17, while two conductors 43 and 44 from a control source (not shown) lead to and connect the binding studs or screws 14' and 18' of the stationary contacts 14 and 18, a trip coil 43^a being, as usual, connected in on the conductor 43. The several stationary contacts 19, 20, 21, 22 and 23 are, in turn, connected respectively by the circuit leads 45, 46, 47, 48 and 49 of a pair of protective relays 50. All of the foregoing circuit connections are to be herein-after designated as the permanent circuit connections of this particular testing system, as distinguished from the following temporary test circuit connections: a pair of conductors 51 and 52 are lead from the stationary contacts 19 and 23 to an operation indicator (not shown), and a second pair of conductors 53 and 54 from the stationary contacts 21 and 22, the conductor 53 leading to and connecting directly one side of the circuit of a test current source (not shown), and the conductor 54, one terminal of a meter 55, which has its other terminal connected to the other side of the latter circuit by a conductor 56.

In the operation of the test block in this hook up of circuits, and with the temporary

5 circuit conductors or leads 51, 52, 53 and 54 disconnected from the stationary contacts 19, 23, 21 and 22 respectively, the transformer short circuiting-bridging contacts or switch blades 37 and 38 in "off" position, the "line" bridging contacts or switch blades 26, 27, 28, 29 and 30 closed, and the main line circuit breaker *d* closed, the relays 50 will be operatively connected to line *a*, *b*, *c* through 10 transformer *T*. Now to make a test on the relays 50, the temporary conductors or leads 51, 52, 53 and 54 will be connected to the binding studs or screws 19', 23', 21' and 22' of the stationary contacts 19, 23, 21 and 22, in 15 the order named, when the bridging contacts or switch blades 37 and 38 will be closed on the stationary contacts 15, 16 and 17, thereby short-circuiting the transformer *T*, and then the bridging contacts or switch blades 26, 20 27, 28, 29 and 30 opened. The relays 50 will now be completely disconnected from the otherwise permanent line circuit connections, and the test current from the test current source aforesaid applied through the 25 meter 55 and the circuit conductors 53, 54 and 56 associated therewith.

In Figure 6, wherein is shown a method of testing various electrical measuring instruments, the stationary contacts 14 and 18, of 30 the test block, will be connected directly to the main line, the contact 14 by the conductor 43' to the main lead *a'*, and the contact 18 by the conductor 44' to the main lead *c'*, while the stationary contacts 15, 16 and 17 35 are connected by the conductors 40', 41' and 42' to the three terminals of the current transformer *T'*, as in the first instance. The several stationary contacts 19, 20, 21, 22 and 23 are connected to the circuit leads 45', 46', 40 47', 48' and 49' to the bank of electrical measuring instruments to be tested, after the same manner of the previous connection of the protective relays 50.

For the purposes of the present invention, 45 the foregoing described connections also constitute the permanent connections for the test block, while the temporary test connections are to be made as follows: A conductor 51' will be led from the stationary contact 15 to one terminal of a test meter 55', a second conductor 52' from the stationary contact 17 to a second terminal on the meter 55', a third conductor 53' from the stationary contact 20 to a third terminal on the meter 55', 55 and a fourth conductor 54' from the stationary contact 22 to a fourth terminal on the meter 55', while the three main terminals of the meter 55' will be connected by the conductors 57, 58 and 59 directly to the main line leads *a'*, *b'* and *c'*, respectively.

In the operation of the test block in this 60 instance of its practical application, it is not necessary that the transformer *T'* be short-circuited through the closing of the bridging contacts or switch blades 37 and 38 onto the

stationary contacts 15, 16 and 17, but, after the temporary test wiring is properly connected as hereinbefore indicated for the same, the line bridging contacts or switch blades 26, 27, 28, 29 and 30 are opened, with the result that the current from the main line transformer *T* is shunted through the test meter 55' as is required.

To admit of the engagement of the key 35 with the several bridging contacts or switch blades 26, 27, 28, 29, 30, 37 and 38, the top wall of the cover 12 will be provided with a corresponding number of openings 60 therein for the purpose.

Without further description, it is thought 50 that the features and advantages of the invention will be readily apparent to those skilled in the art, and it will of course be understood that changes in the circuit connections, and in the type and value of the devices employed may be resorted to, without departing from the spirit of the invention or its scope as claimed.

Having thus fully described the invention, 55 what is claimed is:

1. In a device of the class described, a base 60 of an insulating material, a plurality of line switches spaced along said base and separate switching elements mounted on said base and cooperative with the contacts at one side of the adjacent of certain of said line switches, whereby to short circuit the same whenever desired or necessary.

2. In a device of the class described, a base 65 of an insulating material, parallel rows of evenly spaced contacts mounted on said base, a switch blade for each pair of oppositely disposed contacts, and separate switch blades cooperative with certain of the contacts in one of the rows thereon only to short circuit the same whenever desired or necessary.

3. In a device of the class described, a base 70 of an insulating material, parallel rows of evenly spaced contacts mounted on said base, switch blades mounted on said base one between each pair of the oppositely disposed contacts, said switch blades being arranged for limited horizontal rotative movement relative to the complementary of said contacts, and separate switch blades similarly mounted on said base and between certain of the said contacts at one side only of the first named switch blades whereby to short circuit the same whenever desired or necessary.

GUY N. HUGHES.
